UNITED STATES PATENT OFFICE

ARTHUR A. McMANN, OF UTICA, NEW YORK, ASSIGNOR TO REMSEN CORPORATION, OF NEW YORK, N. Y., A CORPORATION OF DELAWARE

PHONOGRAPH RECORD

Application filed November 28, 1930. Serial No. 498,763.

This invention relates to phonographs and particularly to phonograph records made from sheet stock and has for an object, to prevent records, of this type, from warping; second to substantially separate the portion 5 of the record surface receiving the sound grooves from the central portion of the record; another object of the invention is to provide apertures in the sheet stock of the record whereby its adhesion on the turntable is increased. Other objects of the invention will appear from the following specification and illustrated in the accompanying drawing, in which:

15 Fig. 1 is a plan view of a turntable with the record mounted thereon in accordance with the invention;

Fig. 2 is a side elevation of the construction shown in Fig. 1; and,

20 Fig. 3 is an alternative form of the invention.

The introduction of phonograph records made from sheet stock such as the aluminum records disclosed in the Wadsworth Patent No. 1,421,045, of June 27, 1922, has made it desirable to increase the adhesion between the smooth surface of the record and felt surface of the phonograph turntable to prevent slipping; also it is desirable, when records of this type are made from very thin stock, to prevent the record from warping or buckling, so that it will always lay flat on the turntable. It is desirable to imprint, by lithography or by a printing process a 25 disc 30 play on the central portion of the record. This subjects the central portion to certain 35 stresses which tend to create warping. These conditions are overcome in the present invention by separating, as far as possible, the 40 central portion of the record from the outer portion, which receives the sound grooves. This is secured by stenciling an aperture in the record between the outer portion and the central portion. This aperture may take the 45 form of a pair of arcuate slots, located between the outer and inner portions of the record, or it may take the form of one or more rows of perforations, in the same location. When a record, so perforated, is placed 50 on the felt surface of a turntable the felt

enters the apertures and the tendency for the record to slip is thereby decreased, at the same time internal strains on the inner portion of the record are not transmitted to the outer portion, with the result that the outer 55 portion remains flat. It should be understood that the same construction which separates strains developing in the central portion of the record from the outer portion, also separates such strains as may develop on the 60 portion with the sound grooves from the rest of the record.

In the drawing, 11 is the turntable mounted on the stem 17 of the phonograph mechanism 18. The turntable is provided with a 65 felt surface at 12 upon which the sheet phonograph record 13 is placed with the stem 17 projecting through its central aperture.

The phonograph record has an outer portion 14 upon which the sound grooves are 70 inscribed and an inner portion 16 surrounding the stem which may be lithographed or otherwise provided with a printed surface. Between the outer portion 14 and the inner portion 16, the arcuate slots 15 are provided, 75 which are stenciled from the stock of the record, so that the inner and outer portions are connected at two points where these arcuate slots terminate. The felt surface 12 of the turntable partially projects into the slots 80 15 when the record is in place.

In the modified construction in Fig. 3, the central aperture of the record is indicated at 17a, the inner portion at 16 and this portion is separated from the outer portion by the 85 double row of punched apertures 21 and 22 which, it will be noted, are placed in staggered relation. These apertures are provided for the same purpose as the arcuate slots 15, in Fig. 1. It is apparent that the stock 90 may be stenciled in a variety of forms in carrying out this invention whereby apertures are provided in the stock of the record to be engaged by the felt of the turntable.

The record, or the record blank, 13 when 95 subject to pressure on the inner portion, as in printing, does not transmit its internal stresses to the outer portion of the record, owing to the stenciled apertures which separate these two portions. For the same 100

reason any stresses that may arise from impressing the sound grooves on the record are not transmitted to the central portion. It will be noted that records of this type, particularly when made of sheet aluminum, are light and smooth and their adhesion on the turntable is comparatively small, but by providing apertures through the stock of the record a gripping effect is obtained between the record and the turntable surface which assists in preventing the slipping of the record blanks.

Having thus described my invention, I claim:

15. A sheet metal disc phonograph record having an outer part to receive sound grooves and an inner part with an aperture to receive the stem of a turntable, said inner portion being of the same stock as the sound grooved part and said record disc having slotted apertures between said outer and inner parts.
20. A phonograph record disc of sheet metal having an outer part to receive sound grooves and an inner part with an aperture to receive the stem of a turntable and perforations between said outer and inner parts located substantially adjacent said outer part.
25. A phonograph record disc of sheet metal having an outer part to receive sound grooves and an inner part with an aperture to receive the stem of a turntable and arcuate perforations between said outer and inner parts.
30. A phonograph record disc made from an integral sheet of metal having a concentric part upon which sound grooves are placed and a second concentric part and arcuate apertures in said disc between said parts.

In testimony whereof I affix my signature.
